CLAIM

An ornamental design for a glass block spacer, as shown and described.

DESCRIPTION

FIG. 1 is a front perspective view of the glass block spacer showing my design in use;

FIG. 2 is a fragmentary perspective view of the glass block spacer of my design;

FIG. 3 is a fragmentary front elevational view thereof;

FIG. 4 is a fragmentary rear elevational view thereof;

FIG. 5 is a fragmentary right side elevational view thereof;

FIG. 6 is a fragmentary left side elevational view thereof;

FIG. 7 is a top plan view thereof; and,

FIG. 8 is a bottom plan view thereof.

The undisclosed opposite end is identical in appearance to the end shown as FIG. 2. It is shown broken away for clarity of illustration and to indicate indeterminate length.

The broken line showing of glass block and additional spacers are for illustrative purposes only and form no part of the claimed design.
